UNITED STATES PATENT OFFICE.

JAMES MARSDEN, OF WIGAN, ENGLAND.

MARKING CLOTH AND APPARATUS THEREFOR.

SPECIFICATION forming part of Letters Patent No. 627,779, dated June 27, 1899.

Application filed December 30, 1897. Serial No. 664,725. (No model.)

To all whom it may concern:

Be it known that I, JAMES MARSDEN, a subject of the Queen of Great Britain, residing at Wigan, in the county of Lancaster, England, 5 have invented certain new and useful Improvements in Apparatus for Marking Cloth, (for which I have received Letters Patent in England, No. 7,311, dated March 20, 1897; in France, No. 266,486, dated April 30, 1897; in 10 Hungary, No. 9,433, dated April 30, 1897; in Spain, No. 21,134, dated August 19, 1897; in Italy, Vol. XXXIII, No. 45,211, and Vol. LXXXVIII, No. 206, dated September 30, 1897, and in Belgium, No. 129,188, dated June 15 30, 1897,) of which the following is a specification.

In the process of marking out cloth by means of a templet if a liquid or semiliquid material be used with the templet it is apt to fill up 20 the openings of the templet and the templet is practically spoiled after one use unless it be very carefully cleaned, also a liquid material is apt to spoil the templet, while if a pulverulent material be used it is very easily removed from the cloth, so that if the cloth be knocked about at all the pattern disappears from it.

My present invention relates to an improved machine for marking out cloth in accordance 30 with the process covered by my application filed May 3, 1897, Serial No. 634,846, which is designed to place a permanent pattern on the cloth and yet do it by means of a marking material which shall not affect the templet in 35 any way. In this process I employ a marking-powder which becomes sticky when heated, said powder consisting, preferably, of, first, a body color, such as chalk, pipe-clay, whit- 40 ing, or other neutral powder, and, second, powdered rosin or other like powder.

To this end my invention comprises a heating-roller adapted to be brought into rolling contact with the cloth after the desired pattern has been stenciled upon it and a rubber of absorbent material held against the heating-roller and adapted to be thrown off from the roller when the latter is not in movement. By this means the heating-roller is freed from any sticky particles of the marking-powder before it again comes in contact 45 50

with the cloth. In combination with the heating-roll I preferably employ a long flat table upon which the cloth may be placed, a perforated stencil adapted to be laid out upon the cloth and through which the marking- 55 powder is rubbed, and a series of rollers revolving at the same peripheral speed in the same direction and inclosing a trough-shaped space for automatically rolling up the marked material as it passes under the heating-roll. 60

In marking out black or dark-colored cloths a mixture of three parts of whiting and two parts of resin is all that is required. Where white or light cloths have to be marked, the addition of a coloring-matter or the use of a 65 fine dark or black powder—such as, for instance, lampblack, oxid of iron, or the like—can be used instead of chalk or with the chalk.

In order that my invention may be more clearly understood, however, I append a perspective view of the actual table and rolling device used by me. 70

A is the table; B, the cloth; C, the templet laid thereon; D, a heating-roller heated by gas-jets from pipe F; D', a roller for guiding the marked cloth onto rollers E and E', which rollers are suitably geared together and run from the axle of roll D'; H, a guard-rail pivoted in the side frame and provided with a bar of wood or iron K, the under side of 80 which bar is covered with gladding (thick flannel more like felt) or the like; I, shelves useful for depositing templets not in immediate use rolled up, a few of which are seen at J, and L a handle by means of which motion 85 is imparted to the whole machine through the revolving of the roller D and the gearing connected therewith.

The bar K of the guard-rail, which extends the whole length of the roller D and rests 90 thereon, serves for cleaning said roller as the marked cloth is being passed through for the purpose of fastening in the marks. Immediately the marked cloth has passed between the rollers D and D' the guard-rail H, and 95 consequently the bar K, is raised from off the roller D, as shown in dotted lines, in order to prevent the padding on the bar K from being burned by the heated roller D.

The rollers E and E' are made to revolve in 100

the same direction, so that the cloth after being marked is formed into a roll in the space between the rollers D', E, and E'.

Various thicknesses of cloth may be passed 5 through the rollers D and D', and to allow of this each journal of said roller D has its bearing in a vertical notch or recess made in the top of the side frame, thus allowing the roller vertical play.

10 The mode of operation is as follows: A templet having been made, a roll of cloth is placed on table B and a sufficient length unrolled to be covered by the templet, which templet is formed of a light cloth well loaded with pipe- 15 clay and glue and rolled. Resin or other powder of a sticky nature when heated is rubbed over the templet by a pad already patented in the United States, thus forming marks on the cloth. The templet is now removed and rolled up. The end of the cloth 20 is passed between rollers D and D', where it is heated, and the powder caused to adhere to the cloth. Any little powder that does adhere to roller D is rubbed off by the doctor or rubber on the frame K. The material 25 is automatically folded between the rollers D', E, and E', and the rollers E and E', revolving at the same or a slightly-faster peripheral speed than the roller D, roll up the cloth automatically into a tolerably tight roll. This is 30 then taken out.

I declare that what I claim is--

1. In an apparatus for fixing a sticky powder such as described stenciled on cloth the 35 combination with a heating-roller brought in rolling contact with the cloth of an absorbent material held against the roller in rubbing contact whereby the sticky matter sticking to the roller is rubbed off before it again comes

down on the cloth and means whereby the absorbent material can be thrown off from the roller when the latter is not in movement.

2. The combined apparatus for stenciling cloth, consisting of a long flat table A on which the cloth may be placed, a perforated 45 stencil adapted to be laid out on the cloth, a heated roll D, and means for pressing the marked face of the cloth against the same, and rolls D', E and E' all revolving at the same peripheral speed in the same direction 50 and inclosing a trough-shaped space, whereby the material when once a roll is started is wound up automatically without the necessity of a hard nucleus.

3. The combined apparatus for stenciling cloth consisting of a long flat table A on which the cloth may be placed, a perforated 55 stencil adapted to be laid out on the cloth to enable the marking of the latter with a resinous or other sticky powder, a heated roller D 60 and means for pressing the marked face of the cloth against the same, an absorbent material held against the roller whereby any of the powder sticking to the roller is rubbed off before it comes around again, and rolls D', E 65 and E' all revolving at the same peripheral speed in the same direction and inclosing a trough-shaped space, whereby the material when once a roll is started is wound up automatically without the necessity of a hard nucleus.

In testimony whereof I have signed my name to this specification in the presence of two subscribing witnesses.

JAMES MARSDEN.
